UNITED STATES PATENT OFFICE

ELAINE VON DER LIPPE-LIPSKI, OF WASHINGTON, DISTRICT OF COLUMBIA

ANIMATED SIGN

Application filed March 22, 1930. Serial No. 438,072.

My invention is an improvement in changeable sign exhibitors of that particular type having rotatable bars triangular in cross section to provide media faces which are successively brought into coplanar position at the front of the sign for changing the character of the sign or picture.

The primary object of my invention is to provide a changeable sign of this general type in which a multiplicity of rotatable bars of various widths are provided and turned individually so that one or more parts of the picture may be changed, as for instance to animate a figure depicted thereon, the present invention being an improvement on the arrangement shown and described in my prior application for patent filed October 24, 1929, Serial No. 402,281.

In the present instance I provide for operating the individual units comprising the signboard so that said units may be turned in both directions instead of only one direction as provided for in my aforesaid application, the turning of the units in both directions permitting of a greater change in the picture inasmuch as it will permit certain of the units to be operated in one direction and the changes reversed.

With this principal object in view my present invention contemplates the provision of operating mechanism for actuating the pawls which turn the triangularly shaped bars or units, comprising rocking members actuated in opposite direction by suitable means, as for instance by endless belts having projecting pins adapted to engage said rocking members all as hereinafter particularly described and specifically set forth in the appended claims.

In the drawings:—

Figure 1 is a front elevation of a changeable sign exhibitor constructed in accordance with my present invention.

Fig. 2 is a rear view of the signboard, showing the mechanism for operating the individual units.

Fig. 3 is a side view of Fig. 2.

Fig. 4 is an enlarged detail view illustrating the devices for turning the triangular shaped bars or units.

Fig. 5 is a similar view looking at the opposite side of the rocking member, and

Fig. 6 is a diagrammatic view illustrating a modification in the arrangement of the operating belts.

In carrying out my invention the bars composing the sign-board are mounted in a rectangular frame 10 between the side pieces thereof, and as the bars extending across the signboard are in the present instance divided into independent rotatable units or sections 11 they are mounted on rods 12, each bar or unit preferably having a bearing sleeve 13, as shown in Fig. 2. Each triangular shaped bar or unit A (Figs. 4 and 5) presents three media faces a , a' , and a'' on each of which a portion of a sign is painted or depicted so that the turning of the individual bars or units will bring the different media faces thereof in coplanar relation to effect a change in the picture, it being understood that the units may be arranged in series or groups to change certain portions of the pictures only, and that in the present instance said units are adapted to be turned in both directions to bring either one or the other media faces than the one exposed to position for changing the character of the picture.

The bars or units are each provided at one end thereof with short pins 14 engaged by pawls 15, and so that the movement of said pawls in opposite directions will impart similar movements to the bars or units to bring either one of the unexposed media faces to front position the pawl is provided with hooks 16 and 17 spaced apart to correspond with the spacing of the pins 14 for engagement with said pins, whereby when the pawl is pulled rearwardly the lower unexposed media face of the bar will be brought to exposure position and when said pawl is pushed forwardly the upper unexposed media face of said bar will be brought into exposure position. For operating the pawl or pawls I provide a rocking member in the form of a wheel 18 to which the pawl is pivoted, said wheel being mounted on a shaft 19 and provided at opposite sides thereof with projecting pins 20 and 21 by which it is operated, and for operating the wheel in the direction indicated

by the arrow in Fig. 4 pins 22 projecting from an endless belt 23 directly engage the pin 20, while for operating said wheel in the opposite direction (indicated by the arrow Fig. 5) a bell-crank lever 24 is interposed between the aforesaid belt and the wheel, with one member thereof engaging the pin 21 on the wheel to turn the latter and the other member providing for the operation of said bell-crank lever for which purpose it has an outwardly projecting pin 25 adapted to be engaged by pins 26 on the belt. It will be understood that the pins 22 on the belt which engage pin 20 are out of line with the pins 26 operating the bell-crank lever, and that each series of pins are spaced so as to impart the desired turning movements to the triangular shaped bars or units; consequently said bars or units may be rotated in one direction for several turns to bring the media faces successively to exposed position at the front of the sign or alternately in opposite directions for reversing the exposures to thereby produce a more effective changeable sign or picture than with an arrangement which provides for turning the bars or units in one direction only.

As shown in Fig. 2 of the drawings several operating belts 23 mounted on a roller 27 common to all may be employed so that one or more may be replaced when it is desired to change the actions of a picture on the sign, the spacing of the two series of pins 22 and 26 on the belt or belts controlling the rotation of the bars or units they operate. However, as shown in Fig. 6 vertical and horizontal belts may be employed, the horizontal belt 28 passing over rollers 29 at opposite ends thereof having pins which operate the wheels 18 in the same manner as the vertical belts hereinbefore described, in this instance the vertical belts 30 being mounted above said horizontal belt to operate certain of the bars and of course similar vertical belts may be located below the horizontal belt. One or more horizontal belts may be employed in the construction of the sign and may be operated at different speeds with reference to the vertical belts, said horizontal belt or belts serving to effect changes across the picture in representing motions or actions of objects in the picture independently of those effected by the vertical belts. The companion series of outwardly projecting pins 55 on the belts are spaced apart approximating the thickness of the operating wheels carrying the pins at opposite sides thereof for the direct engagement of one set of pins at one side of the wheel and engagement of the other set of pins at the other side of the wheel, and of course the operating wheels which are actuated by the vertical belts are disposed vertically while those operated by the horizontal belts are horizontal. The belts may be operated from any suitable power, as electric mo-

tors with driving gear connected to pulleys on the rollers which operate endless belts.

In constructing an animated sign in accordance with my invention the number and size of the individual rotatable units will of course depend upon the number of figures or other objects in the picture that are to be changed for the purpose of depicting action, and it will be obvious that in providing for reversing the rotation of the bars or units motion will be repeated forward and backward in regular order, as for instance the movement of the arms or legs of a human being, etc.; thereby producing a changeable sign exhibitor of this general type which will be effective and pleasing to attract attention.

I claim:

1. A changeable sign exhibitor comprising rotatable bars or units having a plurality of media faces adapted to be brought successively into coplanar relation with respect to front of the sign, pins projecting from the ends of the bars or units and corresponding in number to the media faces and in spaced relation thereto, means engaging the pins for rotating the bars or units in one direction, and means engaging the pins for reversing the rotation of said bars or units.

2. A changeable sign exhibitor comprising rotatable bars or units having a plurality of media faces adapted to be brought successively into coplanar relation with respect to the front of the sign, pins projecting from the ends of the bars or units and corresponding in number and spaced apart with relation to the media faces, pawls having opposing hooks engaging the projecting pins on the bars or units, and means for operating the pawls including an endless belt.

3. A changeable sign exhibitor comprising rotatable bars or units having a plurality of media faces adapted to be brought successively into coplanar relation with respect to the front of the sign, pins projecting from the ends of the bars or units and corresponding in number and spaced apart with relation to the media faces, pawls having opposing hooks engaging the projecting pins on the bars or units, means for operating the pawls including an endless belt and pins projecting from said belt.

4. A changeable sign exhibitor comprising rotatable bars or units having a plurality of media faces adapted to be brought successively into coplanar relation with respect to the front of the sign, pins projecting from the ends of the bars or units and corresponding in number and spaced apart with relation to the media faces, pawls having opposing hooks engaging the projecting pins on the bars or units, wheels to which the pawls are pivoted for operation thereof, and an endless belt carrying means for operating the wheels.

5. A changeable sign exhibitor comprising rotatable bars or units having a plurality of media faces adapted to be brought successively into coplanar relation with respect to the front of the sign, pins projecting from the ends of the bars or units and corresponding in number and spaced apart with relation to the media faces, pawls having opposing hooks engaging the projecting pins on the bars or units, wheels to which the pawls are pivoted for operation thereof, pins projecting from said wheels, an endless belt, and means operated by said endless belt for moving the pawls in either direction.
15. 6. A changeable sign exhibitor comprising rotatable bars or units having a plurality of media faces adapted to be brought successively into coplanar relation with respect to the front of the sign, pins projecting from the ends of the bars or units and corresponding in number and spaced apart with relation to the media faces, pawls having opposing hooks engaging the projecting pins on the bars or units, wheels to which the pawls are pivoted for operation thereof, pins projecting from opposite sides of said wheels, an endless belt having projecting pins engaging the pins on one side of said wheels, bell-crank levers engaging the pins on the other side of the wheels, and pins on the belts engaging the bell-crank levers for operating the same.
